DESIGN FOR A COMBINED KEYBOARD AND NECK FOR A STRINGED MUSICAL IN- STRUMENT

Ivan J. Hlad, Chicago, Ill.

Application January 5, 1935, Serial No. 54,728

Term of patent 7 years

To all whom it may concern:

Be it known that I, Ivan J. Hlad, a citizen of United States and resident of Chicago, Cook County, Illinois, have invented a new, original, and ornamental Design for a Combined Keyboard and Neck for a Stringed Musical Instrument, of which the following is a specification, reference being had to the accompanying drawing, forming part thereof.

Fig. 1 is a front elevational view of the article showing my design.

Fig. 2 is a fragmentary rear elevational view.

Fig. 3 is a fragmentary enlarged front elevational view.

Fig. 4 is a fragmentary edge view.

I claim:

The ornamental design for a combined keyboard and neck for a stringed musical instrument, as shown and described.

In witness whereof, I have hereunto set my hand and seal this 10th day of June, A. D. 1935.

IVAN J. HLAD.
